UNITED STATES PATENT OFFICE.

HARRY OAKES, OF WOLSTANTON, ENGLAND, ASSIGNOR TO WILLIAM S. PITCAIRN CORPORATION, OF NEW YORK, N. Y., A CORPORATION OF NEW YORK.

DESIGN FOR A PLATE OR SIMILAR ARTICLE.

Application filed March 28, 1923. Serial No. 5,624. Term of patent 3½ years.

To all whom it may concern:

Be it known that I, HARRY OAKES, a subject of the King of Great Britain, residing at Wolstanton, county of Stafford, England, have invented a new, original, and ornamental Design for a Plate or Similar Article, of which the following is a specification, reference being had to the accompanying drawing, forming part thereof.

Figure 1 is a plan view of a plate, showing my new design but with the border shown only in part for convenience in illustration, the balance of the border being a repeat. Figure 2 is a side view of the same.

I claim:

The ornamental design for a plate or similar article as shown.

HARRY OAKES.
